G. W. RATHJENS,
CARPET FASTENING DEVICE,
APPLICATION FILED FEB. 11, 1921.

1,401,490.

Patented Dec. 27, 1921.

Inventor
George W. Rathjens,
By Barnett & Truman,
Attorneys

UNITED STATES PATENT OFFICE.

GEORGE W. RATHJENS, OF NORFOLK, NEBRASKA.

CARPET-FASTENING DEVICE.

1,401,490.

Specification of Letters Patent. Patented Dec. 27, 1921.

Application filed February 11, 1921. Serial No. 444,218.

To all whom it may concern:

Be it known that I, GEORGE W. RATHJENS, a citizen of the United States, residing at Norfolk, in the county of Madison and State 5 of Nebraska, have invented certain new and useful Improvements in Carpet-Fastening Devices, of which the following is a specification.

My invention relates to carpet fastening devices and it has for its principal object the provision of a new and improved form and arrangement of parts by which a carpet or other floor covering may be securely held in position upon a floor of concrete or other 15 hard material, which will not receive and hold a nail or tack. The preferred means by which I have accomplished my object are illustrated in the drawing and are herein-after specifically described. That which I 20 believe to be new, and desire to cover by Letters Patent is set forth in the claims:

In the drawing,—

Figure 1 is a fragmentary view, partly in section and partly broken away, showing my 25 improved device in use for attaching a carpet to a floor.

Fig. 2 is an enlarged detail view of my improved construction, being partly in section.

Fig. 3 is a central vertical section through two aligned portions of my improved attaching means held in position upon a floor by a single securing means.

Fig. 4 is a top plan view showing the form 35 of securing means employed at a corner of a room;

Fig. 5 is a view similar to Fig. 4, but showing a modified form of structure; and

Fig. 6 is a view similar to Fig. 2, but 40 showing a slightly modified form of construction.

Referring to the drawings, in which corresponding parts are indicated by the same reference characters, 10 indicates a floor of concrete or similar material, with a wall 11 rising from one edge thereof. In Fig. 1, a carpet or rug 12 is shown secured in position along one side of the room adjacent to the wall 11 by the use of my improved attaching means, padding 13 of any suitable type being shown as interposed between the rug or carpet 12 and the floor 10. As is best shown in Fig. 2, my improved fastening device comprises a channel member 14 which 55 in the construction shown is formed of sheet

metal having inwardly extending flanges 15 at the upper edges of the side members. The channel member 14, formed in this manner, is substantially in the form of a flattened tube open on its upper face. 60

Within the channel member 14, I have provided a nailing strip which in the construction shown is formed of a plurality of plies 16, 17 and 18 which completely fill the space within the channel member, and are held in position by means of the flanges 15. The nailing strip is preferably formed of thin sheets of wood, but it may be formed of any other suitable material which will receive and hold a nail or a tack in position. 70 For securing the nailing strip more firmly in position, and for bracing and holding the channel 14 in normal shape, I have provided a plurality of ties 19 which are secured in position by soldering, or by any other suitable process. 75

My improved fastening devices are held in position upon the floor 10 by the use of flanged caps 20 fitting snugly upon the channel members 14. As is shown in Fig. 3, one 80 of the caps 20 is adapted to secure in position the adjacent ends of two aligned fastening devices, or it may be used for securing the end of a single fastening device. The cap 20 is secured in position by means of an expansion bolt construction, such as is shown in Fig. 3, or by any other suitable means, as may be desired. In the construction shown, a screw or bolt 21, passing through a suitable opening in the cap 20, is secured in the 85 floor 10 by means of two fluted or corrugated blocks or shell members 22, of well known construction. As is shown in Fig. 4, a special cap 20^a is used at each corner of the room adapted for use with the converging 90 fastening devices, a washer 20^b being used preferably beneath the cap for supporting it evenly in position. In the modified form of securing cap shown in Fig. 5, the screw 21 is located inside of the angle of the strips 95 rather than at the corner, with the result that one of the strips 18 can be extended to the corner for securing the corner of the carpet.

In the construction shown in Fig. 6, a channel member 23 of slightly modified form 100 is employed, in which the channel member is given a triangular shape in cross section, the inwardly extending flange 24 being formed at the upper edge of the side member, while the inwardly extending flange 25 105

is formed directly upon the lower face of the channel. In this construction, the nailing strip 26 is formed of a single sheet of material in lieu of being formed of a plurality 5 of plies, as is shown in Fig. 2.

By the use of my improved construction, I have provided a fastening device of very great strength which can be very easily applied to a floor of concrete in the process of 10 building the floor, and which is suitable also for application to a floor after the completion of the floor. By the use of a metal channel member, the desired rigidity is provided, and by the provision of the nailing strip of wood or other fibrous material, the desired facility in the use of the device is secured.

While I have shown a channel member unbroken from end to end with continuous 20 flange and web portions throughout, it will be understood that I do not wish to be restricted to the use of this particular form of channel member, strictly speaking, the important feature being that the so-called channel member shall extend about the nailing strip to a sufficient extent and shall effectively embrace and surround the nailing strip along a sufficiently great proportion of 25 its length that the strip shall be given the desired reinforcement and may be secured in position through the medium of such reinforcing member.

I claim:

1. A device of the class described, comprising a metallic channel member and a nailing strip secured in said channel member.
2. A device of the class described comprising a flattened tubular member, open on its upper face along a part of its length, and a strip positioned within said member for receiving and retaining a nail.
3. A device of the class described comprising a metallic channel member having inwardly turned flanges along its open face,

and a nailing strip positioned in said channel and held in position by said flanges.

4. A device of the class described comprising a metallic channel member, and a nailing strip comprising a plurality of plies secured 50 in said channel member.

5. A device of the class described comprising a sheet-metal channel member, a nailing strip in said channel member, and ties extending across the opening of said member 55 serving to reinforce the channel member and to hold the nailing strip in position therein.

6. A device of the class described comprising a metallic channel member, a nailing strip secured in said channel member, a 60 flanged cap fitted on the outer faces of the sides of said channel member, and means for securing said cap to a floor for holding the channel member in position.

7. A device of the class described, comprising a nailing strip which is adapted to receive and retain a nail, a metallic member embracing said nailing strip for reinforcing and strengthening it, and means for securing 65 said metallic member to a floor.

8. Carpet fastening means comprising two nailing strips at an angle to each other, a cap having two arms engaging said two strips respectively, each of said arms having a flange engaging the outer edge of one of said 70 strips, and means for securing said cap to a floor for holding the strips in position.

9. Carpet fastening means comprising a nailing strip, a second nailing strip abutting at its end against said first named strip, a 80 cap having two arms engaging said strips, respectively, each of said arms having a flange on its end portion engaging the outer face of one of said strips, and means for securing said cap to a floor for holding the 85 strips in position, said securing means being positioned within the angle of the converging end portions of said strips.

GEORGE W. RATHJENS.
